Application September 11, 1950, Serial No. 184,223

6 Claims. (Cl. 237—9)

1

This invention relates to a suction device for a radiator of a steam heating system.

Most steam heating systems are of the one pipe type, that is, only a single pipe extends from the boiler to an individual room radiator. Operation of such a system requires that substantial steam pressure be generated and maintained in the boiler. This calls for relatively heavy fuel consumption, as compared to that required by vapor type heating systems.

The individual radiators of a one pipe steam system each have an air vent valve. When a radiator is cool, the air vent valve is open so that boiler pressure is enabled to force cool air out of the radiator. Steam from the boiler then enters and fills the radiator. As the temperature of the radiator increases, the air vent valve automatically closes to prevent the escape of steam.

In many one pipe heating systems of this character, particularly older installations, heating efficiency is impaired for some reason or other. Such substandard systems require even greater quantities of fuel than the relatively large quantities used when operating properly.

One frequent cause of faulty operation is failure of one or more of the air vent valves to function properly. If one or two valves fail to pass the cool air under normal steam pressure, then increased steam pressure is commonly employed. This wastes fuel, and, in addition, results in excessive over heating of other radiators.

A similar difficulty often is present due to the design of the system. Radiators most remote from the boiler are slow to heat, and consequently increased pressures are used which tend to over heat the radiators closer to the boiler, as well as waste fuel.

Another cause of faulty operation is a shifting in the original alignment of the pipes and radiators. This may result from a settling of the building in which the system is installed. Even moderate settling may cause appreciable inefficiencies in the operation of the heating system, and this difficulty has heretofore been expensive to remedy.

One object of our invention is to provide a small, unitary, inexpensive device that may be attached to one or more radiators in a one pipe steam heating system. Use of our device will, in addition to producing other important advantages, overcome the aforesaid difficulties occasioned by faulty air vent valves, faulty design and settling of the building containing the installation. Also, it will effectively convert a steam system into a vapor system with all the advantages of the latter.

2

In brief, our device includes an air vent valve which is more or less conventional. The valve is connected in the usual manner to the valve opening of the radiator. The outlet of the valve 5 communicates through a closed passage with the inlet side of a suction fan, which fan is driven by a small electric motor. A thermostatic switch closes to start the motor when room temperature drops below a predetermined value. As the 10 air vent valve is open when the room and radiator are at that temperature, the suction fan functions to exhaust cool air from the radiator and discharge it to atmosphere, thereby creating a relatively low pressure region within the radiator. This reduced pressure is communicated to some extent throughout the entire heating 15 system. Heated vapors from the boiler quickly travel to the radiator from which the air is being exhausted. When the radiator becomes 20 heated, the air vent valve automatically closes, and a switch associated therewith opens to de-energize the motor and fan, thereby completing a cycle of operation.

Our device may be used on only one radiator 25 of a system, or a plurality or all of the radiators may each be equipped with one of our devices. Regardless of the number of devices used, beneficial results are produced. If full conversion to a vapor system is desired, each radiator should 30 have one of the devices.

The advantages produced by our invention are numerous.

In the first place, when heat is desired in a particular radiator, cool air therein is forcibly 35 exhausted, after which steam quickly flows to and heats the radiator. This eliminates the haphazard practice, sometimes used, of physically taking the conventional air vent valve out of the radiator. Removal of the valve often is 40 followed by forgetfulness with the result that the room, while heated, also is filled with steam and vapors. With our device to bring heated vapors to the radiator when needed, there is no occasion to remove the valve.

Another important advantage of our invention 45 is that it affords a practical, yet extremely inexpensive, means for converting a one pipe steam system into a vapor system. This enables the 50 system to operate with all the advantages of a vapor system, including the use of low or no boiler pressure with consequent economies in fuel consumption. It is only necessary to maintain a generally low, uniform temperature in the boiler (vapor producing heat), a practice 55 that can be expected to save 25 percent or more

on fuel when compared to operation as a steam system.

In the case of new installations, a vapor system can be constructed wherein return pipes are eliminated. Also, the radiator valves on the pipes to the boiler can be eliminated, as no vapors reach the radiators except as called for by our devices.

Another advantage in using one or more of our devices is that small leaks in the system do not appreciably affect system operation, as heretofore.

Another important advantage obtained from using our device on a particular radiator is that the temperature in the room containing that radiator is controlled on an individual room basis. This makes it possible to accurately predetermine and maintain the temperature in a given room entirely independent of the temperatures in other rooms heated by the system. Such individual room control insures uniform heating even in the spring and fall, usually difficult seasons for steam heating systems.

Also, our device makes it easy to eliminate heat from vacant rooms when desired, a feature particularly useful in hotels. Similarly, it is easy to restore heat to such rooms.

The use of our device overcomes inefficiencies in radiation due to undersize or oversize radiators.

Another important advantage resulting from the use of our device is that a certain amount of moist air is forced into the room containing the radiator. Experience has demonstrated that this amount of moist air usually maintains proper, desired humidity conditions in the room.

Other objects and advantages of our invention will be apparent as the description proceeds, reference being had to the accompanying drawings which illustrate one structural form of the invention. It is to be understood, of course, that in additional commercial applications of the invention various details might well vary somewhat from those here shown and described.

In the drawings:

Fig. 1 is a front elevational view of a steam radiator equipped with our suction device;

Fig. 2 is a view in end elevation of the radiator and device shown in Fig. 1;

Fig. 3 is a sectional view through our suction device on line 3—3 of Fig. 2;

Fig. 4 is a sectional view through the device on line 4—4 of Fig. 1;

Fig. 5 is a schematic diagram showing the electrical circuit used with our device;

Fig. 6 is a plan view of a combination electric plug and thermostatic switch that may be used with our device, and

Fig. 7 is a sectional view on line 7—7 of Fig. 3.

Referring now to the drawings, Figs. 1 and 2 illustrate a steam radiator 10 of the type commonly used in an individual room with a one pipe steam heating system. Radiator 10 has a customary radiator valve 11 in the boiler pipe for manually controlling the flow of vapor or steam to the radiator. Valve 11, incidentally, is the valve that would be eliminated in a new installation if our invention were used.

The suction device of our invention is generally designated by 12. It is shown attached to radiator 10 at the customary valve opening of the radiator. An electric cord 13 extends from the device to a nearby convenience outlet 14.

The illustrated form of our invention is shown in detail in Figs. 3 and 4.

Referring first to Fig. 3, our device includes

an air vent valve 16 of more or less conventional construction. Valve 16 has a tubular nipple 17 that is threaded into the valve opening of radiator 10. Tubular nipple 17 communicates with the interior of valve 16 to conduct heated vapors or steam from the radiator to the valve interior.

A bellows device 20, located inside valve 16, has sealed therein a gas that expands appreciably on heating. Bellows device 20 carries a valve stem 21 that actuates a valve element 22. A valve seat element 23 cooperates with valve element 22 to provide a valve assembly.

As illustrated, bellows device 20 is relaxed (not heated), and in this condition, valve element 22 is not seated on element 23, i. e., the valve is open. When increased temperatures reach bellows device 20, the contained gas expands with the result that the valve closes, thereby preventing the escape of any more air or heated vapors from the radiator interior.

From the above description, it will be seen that when the radiator and the room containing the radiator are cool, air vent valve 16 is normally open so that cool air from the radiator interior may be removed. The air removal operation is performed in our device with the cooperation of a suction fan, as will be seen.

The outlet from element 23 of valve 16 communicates through a closed passage with an inlet 25 of a suction fan 26.

The closed passage may take a variety of forms, and for purposes of illustrating our invention, we have shown the entire air vent valve 16 enclosed in a substantially airtight housing 27. Nipple 17 of valve 16 extends through housing 27, the latter being supported by and sealed to the nipple. Housing 27 has a perforated partition 28 to which the outlet portion of valve 16 is secured. The remaining part of housing 27 will be later described.

Fan inlet 25 comprises a tubular nipple that passes through and is secured to housing 27 in an airtight manner. This nipple and valve nipple 17 are desirably colinear. Inlet 25 communicates with a circular housing 30 that encloses suction fan 26. Housing 30 has an annular outlet 31 at its periphery for the passage of air exhausted from the radiator by fan 26.

Suction fan 26 may be of any conventional type, and it preferably has side plates 33 and 34 separated by vanes 35, best shown in Fig. 4. With vanes 35 oriented as shown in Fig. 4, the direction of fan rotation is as indicated by the arrow.

An electric motor 37 is mounted on fan housing 30, and operatively connected to fan 26. The motor axis and fan axis desirably are colinear with fan inlet 25 and air vent valve nipple 17.

The path of air through our device when operating to withdraw air from radiator 10 is shown by arrows in Fig. 3. Air from the radiator interior enters tubular nipple 17 and is discharged into the interior of valve 16. From here, the air passes through the then open valve elements into the region enclosed by housing 27. Thence it passes through fan inlet 25 to the central region of the fan housing. Fan 26 drives the air from this central region to the peripheral region of the housing, from whence it is discharged through annular outlet 31 to atmosphere.

A suction fan of the character described can be relied upon to move a relatively large volume of air, a characteristic that is necessary to successful operation of our device. In this manner a region of relatively low pressure is produced in

radiator 10, and this low pressure condition is communicated through the pipe leading to the radiator to the boiler. As a result, heated vapors are conducted quickly from the boiler to the radiator in question. When higher temperatures reach the radiator and are impressed on bellows device 20 of air vent valve 16, the valve automatically closes, thereby preventing the discharge of heated vapors through our device to atmosphere.

Referring now to Figs. 5, 6 and 7, the electrical circuit and other components used to control the operation of our device will now be described.

A schematic circuit diagram for use with our device is shown in Fig. 5. An electric plug 40 has one terminal connected to one terminal of motor 37 by conductor 41. The other motor terminal is connected by conductor 42 to one terminal of a switch 43. This switch, as will presently be seen, operates in response to the closing and opening action of air vent valve 16. The other terminal of switch 43 is connected by a conductor 44 to one terminal of a thermostatic switch 45, the other terminal of switch 45 being connected by conductor 47 to the second terminal of plug 49. Conductors 41 and 44 make up the electric cord 13 illustrated in Figs. 1 and 2.

In order to condition our device for operation, plug 40 is inserted in a convenience outlet such as 14. If the temperature of the room is at a proper desired value, thermostatic switch 45, which may be enclosed in a common housing with plug 49, is open, so the motor is not energized. When the room temperature falls below a predetermined value, thermostatic switch 45 closes and, since switch 43 also is closed, the motor is energized to drive fan 26. At this time with the room cool, air vent valve 16 is open so that fan action causes air to be withdrawn from the radiator through air vent valve 16. The motor and fan continue operation until such time as sufficient air is exhausted from the radiator to permit heated vapors to reach the radiator interior and air vent valve 16. When valve 16 closes in response to this increase in temperature, a mechanical connection, presently to be described, between valve 16 and switch 43 causes the latter to open, thereby breaking the circuit to the motor. Thereafter, the radiator continues to heat the room for an extended period. At this increased room temperature, thermostatic switch 45 assumes its normal, open position.

When the radiator and the room cool somewhat, air vent valve 16 opens with the result that switch 43 closes, as will be later described. However, motor 37 is not energized because at this time thermostatic switch 45 is open. When room temperature drops still further, switch 45 closes to initiate a successive cycle of operation.

Referring to air vent valve 16 in Fig. 3, it will be seen that valve seat element 23 has an outlet opening of substantial size. An elongated member 50 extends through this enlarged opening, one end of the member being in contact, separate or integral, with valve element 22. Thus valve element 22 is between member 50 and valve stem 21, and the member and stem are colinear. Consequently member 50, looking at Fig. 3, moves up and down with valve element 22 and valve stem 21.

The free end of member 50 is positioned to cooperate with switch 43, which, as illustrated, is of the micro-switch type and is located in the upper portion of housing 27. When member 50 is in retracted position, as shown in Fig. 3, its

free end is out of effective engagement with switch 43, and the switch is closed. Alternatively, when member 50 is extended in response to valve closure, the free end engages one of the elements of switch 43 to open the switch. Upon retraction of member 50 when the valve opens, microswitch 43 automatically closes.

Since the physical relation of switch 43 and the member 50 is more or less critical, switch 43 is preferably mounted in a pivotal manner on a pivot pin 52. A resilient means such as springs 53 bear against one side of switch 43, while an adjustable means such as set screw 54, bears against the opposite side. Adjustment of the means 54 readily locates switch 43 in proper position for actuation by member 50. Switch 43, of course, is properly positioned when it is closed during the time valve 16 is open, and open during the time valve 16 is closed.

In order that switch actuating member 50 will not unduly impede the passage of air through the outlet of valve 16, the member 50 preferably has a diameter that is appreciably smaller than the valve outlet opening. Also, as shown in Fig. 7, member 50 may have longitudinal grooves 57 to increase the area available for air passage.

Thermostatic switch 45, as previously mentioned, may conveniently be incorporated in a common housing with electric plug 40. The assembly of the two elements in a common housing 60 is illustrated in Fig. 6. Switch 45 is, of course, set so that it will close at a predetermined temperature, which temperature may be a few degrees below the desired room temperature. Similarly, switch 45 is designed to open at or slightly above the desired room temperature.

From the above description it is thought that the advantages, construction and operation of our invention will be readily apparent to those skilled in the art. Various changes in detail may be made without departing from the spirit or losing the advantages of the invention.

Having thus described our invention, what we claim as new and desire to secure by Letters Patent is:

1. A suction device for a radiator in a one pipe steam heating system, said device comprising an air vent valve for connection to the valve opening of the radiator, said air vent valve including a thermally actuated valve element, a member movable in response to said valve element, a fan housing and a suction fan therein, said fan housing having an inlet and an outlet, the inlet to said fan housing communicating through a closed passage with the valve element of said air vent valve, an electric motor for driving said fan, a circuit for said motor including a thermostatic switch for making the circuit when the room temperature falls below a predetermined value, whereby said fan withdraws air from the radiator through said air vent valve, and a switch for breaking said circuit upon closure of said air vent valve, said last-named switch being actuated by said member movable in response to said valve element.

2. The combination of claim 1 wherein said valve element has a valve stem within the air vent valve, and the member movable in response to said valve element is colinear with said valve stem, the valve element being disposed between the stem and said member.

3. The combination of claim 1 wherein said

motor circuit includes a plug for attachment to an electric outlet, and a housing for said plug, the said thermostatic switch being mounted in said housing.

4. The combination of claim 1 wherein the axis of said radiator valve opening, the fan axis and the motor axis are colinear.

5. The combination of claim 1 wherein said last named switch is mounted in a pivoted manner, the pivotal position of said switch determining the time of switch operation relative to the action of said member movable in response to said valve element, and means for making pivotal adjustment including a set screw bearing on one side of said switch and a resilient means bearing on the opposite side of said switch.

6. A device of the character described comprising an air vent valve, a fan housing supported by said air vent valve and having an inlet communicating with said valve through a

5
10

closed passage, a suction fan within said housing, a fan driving electric motor carrier by said housing, and an electric circuit for controlling said motor, said circuit including a thermostatic switch and a switch responsive to opening and closing of said air vent valve.
